(57) CLAIM

The ornamental design for a baby utensil with charm, as shown and described.

DESCRIPTION

FIG. 1 is a perspective view of the top, end, and side of a utensil in accordance with my design;

FIG. 2 is a perspective view of the bottom end, and side thereof;

FIG. 3 is a top plan view thereof;

FIG. 4 is a side elevational view thereof, the opposing side being identical;

FIG. 5 is a bottom plan view thereof;

FIG. 6 is a rear elevational view thereof; and,

FIG. 7 is a front elevational view thereof.

The broken line illustration of a rounded end portion of a spoon in each of FIGS. 1-7 forms no part of the claimed design.
